UNITED STATES PATENT OFFICE

154,783

DESIGN FOR A BLOUSE OR SIMILAR ARTICLE

Lucy Larssen, New York, N. Y.

Application January 23, 1948, Serial No. 143,987

Term of patent 14 years

(Cl. D3—25)

To all whom it may concern:

Be it known that I, Lucy Larssen, a citizen of the United States of America, and a resident of New York city, county of New York, State of New York, have invented a new, original, and ornamental Design for a Blouse or Similar Article, of which the following is a specification, reference being had to the accompanying drawings, forming part thereof.

In the drawings:

Fig. 1 is a front view of a blouse showing my new design;

Fig. 2 is an enlarged fragmentary view of the blouse shown in Fig. 1, illustrating the collar trim in detail;

Fig. 3 is an enlarged detail of the tie; and

Fig. 4 is an enlarged detail of a button.

The back of the blouse is of conventional design.

I claim:

The ornamental design for a blouse or similar article, substantially as shown and described.

LUCY LARSEN.
